UNITED STATES PATENT OFFICE.

ROBERT J. CROSS, OF PITTSBURGH, PENNSYLVANIA.

BOOK COVER AND BINDER.

1,424,622.

Specification of Letters Patent. Patented Aug. 1, 1922.

Application filed September 3, 1919. Serial No. 321,445.

To all whom it may concern:

Be it known that I, ROBERT J. CROSS, a citizen of the United States, residing at Pittsburgh, in the county of Allegheny and State of Pennsylvania, have invented a new and useful Book Cover and Binder, of which the following is a specification.

The present invention is a cover and binder for loose leaves or sheets of paper. As far as applicant has knowledge, there are two general types of note books or binders of the loose leaf variety; namely, those which make use of rings and those which make use of rods or posts to extend through openings in the leaves or sheets to maintain them in position. The ring type of cover or binder has the disadvantage that the openings or eyelets of the sheets easily tear out from the rings. There is no real binding of the leaves in this type of binder as they slide loosely on rings, and their liability of being torn from the rings is an annoying disadvantage. In the post type of binder there are generally found stud members or telescoping rods which extend through the opening in the edges of the leaves and which hold the sheets bound together by compression. Binders of this type are, however, not adjustable from the thickness of one sheet of paper to its capacity because the minimum thickness of the book corresponds to the length of the members or posts in their full telescoping or collapsed position. This limitation or disadvantage is readily obvious, especially when one or two leaves or a relatively few leaves are required in the cover.

It is the object of the present invention to produce a note-book or cover, which will open in such a manner that, when laid flat on a table, or used as a field or hand-book, the leaves thereof will not close, and to produce a cover in which one or a plurality of loose leaves may be bound and which will permit the ready and easy removal of any number of leaves or intermediate leaves without necessitating the removal of the other leaves from the cover.

The invention further resides in the summary details of construction, combination and arrangement of parts hereinafter more fully described and pointed out in the appended claims.

In the drawings which illustrate the preferred embodiment of the invention as at present devised,

Fig. 1 is a longitudinal sectional view taken through the binding means of the book cover.

Fig. 2 is a rear end view of the book or binder.

Fig. 3 is on line 7—7 of Fig. 2 of the binder to illustrate the construction of the binding mechanism.

Figure 4 is a fragmentary plan view of the binding end of the book cover illustrating the particular formation of the spring 19.

Referring particularly to the drawings, in which like characters refer to corresponding parts throughout the several views and in the specification, the invention comprises a front or upper cover 1 and a relatively thicker back or tablet portion 2 both, preferably, rectangular in shape and of rigid material. To the one edge of the tablet portion is hinged, as at 3, a binder block 4 which is preferably co-extensive with the said edge and may have the same relative thickness as the body of the tablet 2. The cover 1 is flexibly connected at 5 to a binder strip 6 corresponding to the binder block 4. The binder strip and binder block lie opposite and parallel to each other and are equipped with means for binding loose leaves or sheets of paper therebetween. The back 2 is cut away or mortised inwardly from the upper edge thereof to provide a recess 7 in its outer face extending transversely thereof. This recess may be of sufficient depth to accommodate binder block 4 when the book is opened.

To permit the opened leaves α to be turned back underneath the book, the cover 1 of the book is hinged or flexible transversely at the point 8, the distance between the hinged or flexible portions 5 and 8 being of slightly greater width than the binder strip 6 in order to permit this folding of the book and leaves.

The parts 1, 2, 4 and 5 may be all covered by a covering of cloth, leather or other suitable material and the hinged members 4 and 6 are to be concealed by the covering in such manner as to prevent any liability of scratching or otherwise marring a desk, table, or the like.

The means for binding the leaves between a cover 1 and back 2 of the note-book comprise studs or posts 9, one, preferably, at each end portion of the binder block 4. These studs 9 are slidably mounted in the

block 4 and are, preferably, contained in tubular guides 10 embedded in the block. The inner ends of the studs have laterally projecting therefrom lugs 11 extending 5 through longitudinal slots 12 in the guide 10. A leaf spring 13 is disposed in a recess in the block and has one end thereof formed with an opening in which the guide 10 extends, the end of the spring engaging 10 with the lugs 11 and normally tending to project the stud 9 outwardly from the block. The spring 13 is preferably a flat spring 15 bent in substantially U shape as shown in the drawings; however, it may be found to advantage to use a different form of spring or means to eject the studs 9. Posts or rods 20 depend from the binder strip 6 and are slidably received in the tubular guides or sleeves 15 mounted within the block 4. The posts and studs 9 are adapted to extend through the usual openings formed in the leaves adjacent an edge thereof.

To tightly bind the leaves between the block 4 and strip 6, a threaded rod 16 is pivoted to the strip 6 at an intermediate point in its length and has threaded thereon a thumb nut 17. The block 4 is formed with a pocket 18 at an intermediate point thereof with the side walls A and B thereof formed 25 with slots C and D, said slot C being of such width as to receive the threaded rod 16 and to provide shoulders against which the nut 17 may bear. The nut is formed with a reduced extension E to extend through the 30 slot D, which acts as a guide for the nut. The pocket 18 is of such size as to permit access to the nut 17 for threading it on the rod 16. It is obvious that as the nut is threaded 35 on the rod 16, compression is produced between the block 4 and the strip 6 in order to 40 tightly compress or bind the edges of the loose leaves therebetween. A suitable torsion spring 19 is provided on the strip 6 for automatically moving the rod 16 outwardly 45 as shown in dotted lines of Fig. 3, when the nut 17 has been loosened sufficiently. This spring consists of lengths of wire a—b positively connected to the ends of the pivot 50 piece C of the rod 16. These lengths of wire extend in a line with the axis of said pivot piece and have their free ends 20 laterally extended and imbedded in the strip 6 as clearly shown in Figure 4. When the rod 16 is moved to its binding position, 55 shown in full lines of Figure 1, 2 and 3, a torsional strain is produced in the wire sections, because of their peculiar formation and being imbedded in the strip 6, which torsional strain will move the rod 60 16 to the dotted line shown in Figure 3 when the nut 7 is loosened.

The block 4 may be made of solid material mortised in a suitable manner shown or may be made of sheet metal.

65 From the above description it will be seen

that any number of sheets from one upward to the capacity of the book may be firmly bound therein, the capacity of the book being limited only by the length of the studs 9 and 14, their length corresponding to the thickness of the block 4. The block 4 and the back 2 of the book may be of the same thickness in order to permit the book to lie flat upon a flat surface.

In some forms of the invention, it may be 75 found desirable to omit the studs 9 and post 14, as the compression produced by the nut 17 between the block 4 and strip 6 is found sufficient to maintain the leaves firmly in position within the book. In such a modification, the leaves may be readily inserted or removed at any place in the book.

Having thus described the invention, it is to be understood that certain changes in the construction, combination and arrangement 85 of parts may be made which fall within the scope of the appended claims.

I claim:

1. In a loose leaf binder, a pair of cooperating binding elements, one of said elements 90 having a pair of spaced walls formed with notches therein, the other of said binding elements having a threaded rod thereon adapted to engage in said notches, an adjustable member receivable between the walls of 95 said first element and threadedly adjustable on said rod, whereby said adjustable member will engage one of the walls of said first binding elements to clamp said binding elements together, said adjustable member 100 lying within the confines of said first mentioned binding element when in clamping position.

2. In a loose leaf binder, a pair of cooperating binding elements, one of said elements 105 having a pair of spaced walls formed with notches therein, the other of said binding elements having a threaded rod thereon adapted to engage in said notches, an adjustable member receivable between the 110 walls of said first element and threadedly adjustable on said rod, whereby said adjustable member will engage one of the walls of said first binding element to clamp said binding elements together, said adjustable member 115 having a projecting guide adapted to cooperate with the edges of one of the notches in said first mentioned binding element, said adjustable member and its said projections being adapted to lie within the 120 confines of the walls of said first binding element when in clamping position.

3. In a loose leaf binder, a pair of cooperating binding elements, one of the elements being relatively thick and having its thickened edge recessed to provide two opposite spaced walls, said walls being formed with aligning notches in their edges, the other of said binding elements having a threaded rod pivotally connected thereto and receivable 125 130

- in said notches, an adjustable member on said rod and receivable in said recess between the walls of said first mentioned binding element, whereby said adjustable member 5 will abut one of said walls of said other binding element and clamp said members together, said adjustable member and the free end of said rod lying wholly within the confines of said first mentioned binding element
- 10 when in clamping position.
4. In a loose leaf binder, two binding strips, a threaded rod pivotally connected to one of said strips, and engageable in a notch formed in the other strip, a nut thread- 15 ed on the rod and engageable with shoulders produced by said notch to adjustably maintain said strips in binding relation, and a means for automatically moving said rod out of engagement with notch when the nut is 20 disengaged from said other strip.
5. In a loose leaf binder, a binding member on which loose leaves are laid, an aligning stud slidably mounted in said member for engaging in the eyelets in said loose 25 leaves and adapted to be wholly contained within said member, and means projecting the stud outwardly from the member.
6. In a loose leaf binder, a relatively thick binding strip, an aligning stud embedded in 30 said strip and slidably mounted relatively thereto, and yieldable means normally urging said stud outwardly from said strip to engage in eyelets of loose leaves.
7. In a loose leaf binder, a relatively thick binding strip, a pair of leaf aligning studs 35 slidably mounted in said strip and adapted to be wholly contained within the latter, yieldable means normally urging said studs outwardly from the strip for engaging the eyelets of the leaves, a second binding strip, 40 and means between said strips for adjustably maintaining them in positive binding relation.
8. In a loose leaf binder, a relatively thick binding strip, an aligning stud for engaging 45 in eyelets in loose leaves and slidably mounted in said strip, said stud being wholly receivable within said strip, means normally urging said stud outwardly from the strip, a complementary binding strip having a short 50 rod projecting therefrom and receivable in guide openings in said first strip, and means between said strips for adjustably maintaining them in positive binding relation.
9. In a loose leaf binder, a binding strip, 55 means for engaging in eyelets in loose leaves slidably mounted in said strip, and wholly containable within the latter, means projecting said loose leaf engaging means outwardly from the strip, a second binding 60 strip to cooperate with said first strip, and means for causing a clamping action between said strips, whereby one or a plurality of leaves may be bound between said strips.
- In testimony whereof I have hereunto set 65 my hand.

ROBERT J. CROSS.
